ENGINE ANALYZING UNIT

Benjamin F. W. Heyer, Greenwich, Conn., assignor to Heyer Industries, Incorporated, Belleville, N. J., a corporation of Delaware

Application January 3, 1958, Serial No. 49,135

Term of patent 14 years

(Cl. D26—1)

Fig. 1 is a front perspective view of an engine analyzing unit, showing my new design, the rear being conventional; and

Fig. 2 is a side elevational view, the opposite side being substantially a mirror image thereof.

Portions of the drawing figure are diagonally lined to indicate transparency.

I claim:

The ornamental design for an engine analyzing unit, substantially as shown and described.
